UNITED STATES PATENT OFFICE.

JACK KLEINMAN AND PHILIP F. SHAFRAN, OF NEW YORK, N. Y.

PRINTING DEVICE.

Application filed May 21, 1927. Serial No. 193,096.

This invention relates to printing mechanism and more particularly to a power driven printing device having a rotating type drum.

5 The invention relates specifically to a mechanism for selectively printing one of a plurality of characters carried peripherally upon a rotary drum. The invention is however, particularly applicable to the printing 10 of numbers in response to the operation of a plurality of keys such as for example in connection with a punch for making index point perforations on tabulating cards.

The invention further provides for continuously applying power for normally causing rotation of the type drum and for automatically disconnecting said drum from the source of power whenever the rotation of the drum is interrupted. The type drum may 20 be driven by a pair of gear wheels meshing with a pair of similar gear wheels carried by the power shaft, the teeth of said wheels being so shaped that power will be transmitted therebetween whenever both shafts 25 are free to rotate. Whenever one of the shafts is locked against rotation however, the meshing teeth operate as cam surfaces for separating the two shafts and bringing the type drum into printing position.

30 The invention also consists in certain new and original features of construction and combinations of parts hereinafter set forth and claimed.

In accordance with the present invention, 35 a pair of gear wheels are designed with teeth sufficiently flattened and loosely fitting to permit the edges of the teeth of one wheel to ride on the edges of the co-operating teeth whenever the rotation of one of said wheels 40 is interrupted. The wheels are thus brought out of mesh, and the corresponding shafts are separated. A type wheel may be connected to one of said shafts and a plurality of peripherally spaced stops may be provided 45 for locking said wheel in any desired position. The continued rotation of the power shaft after the type wheel is locked may then be utilized for disengaging the gear wheels and for bringing the type cylinder 50 into a printing position.

Upon further rotation of the power shaft, the teeth pass the cam position and the succeeding teeth come into meshing position. The teeth may then be brought together by 55 a suitable spring, the type wheel unlocked

and continued rotation permitted until other characters are to be printed.

Although the novel features which are believed to be characteristic of this invention will be specifically pointed out in the claims 60 appended hereto, the invention itself, as to its objects and advantages, the mode of its operation and the manner of its organization, may be better understood by referring 65 to the following description taken in connection with the accompanying drawings forming a part thereof, in which like reference characters have been used to denote like parts in the various figures. Since such illustration is, however, primarily for purposes 70 of disclosure, it will be understood that the structure and the method of operation thereof may be modified in various respects without departing from the broad spirit and 75 scope of the invention.

One embodiment of the invention has been shown for purposes of illustration in the accompanying drawing, in which

Fig. 1 is a broken front elevation of the type cylinder and driving means therefor, 80

Fig. 2 is an end elevation showing the interrupting mechanism.

Fig. 3 is a detail view of the interrupting mechanism showing the relative position of the parts during a printing operation.

Fig. 4 shows a modified form of printing apparatus, and

Fig. 5 is a detail view of the interrupting mechanism showing a possible operating position.

90 In the following description and in the claims the various parts of the apparatus and details of the invention will be identified by specific names for convenience, but they are intended to be as generic in their application as the art will permit.

Referring to the drawings more in detail, the printing mechanism may comprise a rotatable cylinder 10 carrying a plurality of peripherally spaced type characters such as 100 for example as the digits 0 to 9 or 0 to 12 and mounted for rotation on rod 11. Said rod may be journaled for rotation in suitable bearings 12 and 13 carried by supports 14 and 15 respectively. Supports 14 and 15 105 may be slidably mounted in standards 16 and 17.

110 Power shaft 18 may be journaled in standards 16 and 17 and provided with a pair of gear wheels 19 and 20 which are rigidly se-

- cured thereto and adapted to mesh with gear wheels 21 and 22 carried on rod 11. The number of teeth on wheels 21 and 22 should correspond with the number of peripherally spaced type characters on cylinder 10. Shaft 18 may be driven from a source of power (not shown) and caused to impart rotation to printing cylinder 10 by means of the aforementioned gear wheels. Suitable means such as spring 23 may be provided for urging gear wheels 21 and 22 toward gear wheels 19 and 20 and causing them to continuously remain in mesh except when a printing operation is taking place.
- In order to arrest the movement of cylinder 10, a plurality of peripherally spaced stops 24 may be provided and adapted to co-operate with a plurality of interposer bars 25, said bars being selectively operated as by keys 26. When a key 26 has been depressed the corresponding interposer bar 25 is forced into engagement with stop 24 and interrupts the rotation of shaft 11 together with cylinder 10 attached thereto.
- Gear teeth on wheels 19, 20, 21 and 22 are constructed with contacting surfaces sufficiently flattened to allow the teeth of one of said wheels to exert a cam action on the teeth of a co-operating wheel and to force said wheels apart whenever relative peripheral movement takes place. One wheel may therefore be locked against rotation and the continued rotation of the other wheel will cause the teeth to ride upon the teeth of the other and exert a cam action thereon for separating the wheels and the corresponding shafts as shown in Fig. 3. Cylinder 10 attached to shaft 11 is then in depressed or printing position.
- The shafts remain separated until the teeth have slipped past or disengaged when the gear wheels may again mesh. They will then be displaced by one tooth from their original meshing position and will so remain provided both wheels are again allowed to rotate.
- When shaft 11 is forced into printing position as aforesaid, interposer 25 is rotated about its pivot 30 to its original position and is engaged by cam 31 and retained in that position. Consequently when shaft 11 is displaced by springs 23 and brought into operating position with respect to the power shaft, stop 24 disengages from interposer 25 and said shaft 11 may again rotate.
- Cam 31 is held by spring 32 in engagement with a double wedge surface on interposer 25 and serves to maintain said interposer in either raised or lowered position. Should a key 26 be depressed, however, when interposer 25 is opposite a stop member 24 and is prevented thereby from moving into engaging position, cam 31 will prevent the interposer from returning to normal position when said key is released and will force

said interposer into engaging position as soon as stop 24 has passed the end thereof.

The interposer will then co-operate with stop 24 when said stop is again brought into operative position and lock shaft 11 to initiate another printing operation.

Should key 26 be depressed and immediately released, cam 31 will co-operate with interposer 25 and hold the same in engaging position until positively released by a printing operation as above mentioned.

The type cylinder may be provided with a double set of characters, each occupying half of the periphery and two stops spaced by 180 degrees may be employed for co-operating with each interposer. The shaft would then be stopped for printing within a half revolution after any key is depressed and the speed of operation correspondingly increased. Obviously any other desired number of sets of characters could be employed and the number of stop members and the number of teeth on the gear wheels similarly increased.

The above mentioned apparatus may be operated by a suitable timed impulse such as that produced by a card having index point perforations. In the modification shown in Fig. 4, a plurality of stops 34 are shown peripherally spaced to correspond with the various peripheral type elements. One blank is therefore used for the entire set of stops and the number of parts correspondingly reduced. The printing operation is controlled by depressing interposer 35 in suitable time relationship to the rotation of shaft 11 for co-operating with the desired stop member 34. Continuous rotation of the power shaft will then depress the type wheel, print the corresponding characters and restore interposer 35 to its original position as desired above.

Interposer 35 may be operated by a solenoid 36 in response to timed electric current or may be operated by other well known means of remote control. Gear wheels 21 and 22 should be so arranged that a tooth is in the uppermost position when the wheel is in any stop position in order to obtain the fullest effect of the cam action of the co-operating teeth.

In accordance with the present invention, a rotary type cylinder may be actuated by a constantly revolving power shaft and utilized for a printing operation which not only avoids interruption of the power shaft but utilizes the power derived therefrom for bringing the cylinder into printing position. Since the relative peripheral movement of the two gear wheels is utilized for effecting a printing operation, the interruption of the movement of the type wheel in any desired position automatically causes the cylinder to print and release. The apparatus is simple in construction and re-

quires but relatively few parts. It may be operated in conjunction with a card punch or may be applied to any of the well known commercial accounting machines such as for example, an adding machine, cash register, typewriter or stock ticker. If the arrangement is operated by remote control, as by means of synchronous electric impulses, it may be applied to a tabulating machine and operated in accordance with cards having index point perforations.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention. Obviously, the device could be employed for embossing, punching and analogous uses and the term printing is intended to cover such structures.

What is claimed is:

- 25 1. A printing mechanism comprising a rotatable type wheel, a gear wheel affixed thereto and a second wheel co-operating therewith, each of said wheels having cam-like gear teeth and means for locking of one of said wheels whereby the disengagement of said teeth will be caused.
- 30 2. In combination with a rotary type wheel, a driving shaft and gear wheels associated with said type wheel and said driving shaft, said gear wheels having mutually sliding teeth and means for interrupting the rotation of said type wheel and the gear wheel associated therewith whereby disengagement of said teeth will be caused and the type wheel forced into printing position.
- 35 40 3. In combination with a driven shaft, a rotary type wheel thereon, means for interrupting the operation of said wheel at a predetermined angular position, operating

means for said wheel comprising a driving shaft, co-operating gear wheels attached to said shafts, said gear wheels having slideable teeth and means whereby relative peripheral movement thereof will cause disengagement of said teeth and force the type wheel into printing position.

4. In combination with a driven shaft, a rotary type wheel thereon, a plurality of peripherally spaced stops thereon, means for co-operating with said stops, and interrupting the operation of said wheel, operating means for said wheel comprising a driving shaft, co-operating gear wheels attached to said shafts, and means whereby relative peripheral movement of said wheels will cause disengagement thereof and force the type wheel into printing position.

5. In combination with a driven shaft, a rotary type wheel attached thereto, a plurality of peripherally spaced stops mounted thereon, a plurality of interposer bars for co-operating with said stops, and interrupting the operation of said wheel, operating means for said wheel comprising a driving shaft and co-operating gear wheels attached to said shafts, said gear wheels having cam teeth and means whereby relative peripheral movement thereof will cause disengagement of said teeth and force the type wheel into printing position.

6. A printing mechanism comprising a rotatable type wheel, a gear wheel affixed thereto and a second wheel cooperating therewith, each of said wheels having cam-like gear teeth, and means whereby locking of one of said wheels and continued rotation of the other of said wheels will cause disengagement of said teeth.

In testimony whereof we have hereunto set our hands.

JACK KLEINMAN,
PHILIP F. SHAFRAN.
